Primary Examiner — Kimberly Barnes(74) *Attorney, Agent, or Firm* — Oliff PLC(57) **CLAIM**

The ornamental design for a helmet, as shown and described.

DESCRIPTION

FIG. 1 is a front, left-side perspective view of a helmet showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear, left-side, top perspective view thereof.

The evenly-spaced broken lines depict parts of the helmet that form no part of the claimed design. The dot-dash chain lines depict boundaries of the claimed subject matter, and thus form no part of the claimed design.
